CALUTRON ION SOURCE SLIT CLEANER

Allan M. Starr, Piedmont, Calif., assignor to the United States of America as represented by the United States Atomic Energy Commission

Application October 8, 1946, Serial No. 701,905

4 Claims. (Cl. 250—41.9)

The present invention relates to calutrons and more particularly to an improved arc slit cleaning device used in association with a calutron ion source.

A calutron is a term which has been defined as "any apparatus or machine wherein isotope separation or enrichment is achieved on a large scale, using commercially useful quantities of one or more isotopes by appropriate separative action on gaseous ions with electrostatic or electromagnetic means or combinations of them." The foregoing definition has been taken from the application for Letters Patent of the United States, Serial No. 557,784, by Ernest O. Lawrence, now Patent No. 2,709,222, issued May 24, 1956. In that patent, the theory of ionic separation and the principles of operation of a calutron are so fully treated and thoroughly explored that no useful purpose would be served by here repeating the discussion contained therein.

In general, however, an ion source of a calutron projects ions into a magnetic field; thereafter, the ions travel in curved paths through the magnetic field, the ions of greater mass describing paths with curves of longer radii than the ions of lesser mass. Isotope collectors are disposed at suitable points along each path, preferably at the 180° point with respect to the source of the beam, and collect the isotopes of the different masses. In this manner, the atoms of different mass that were originally in a polyisotopic mixture are substantially separated from each other, one mass being enhanced with respect to one isotope while the other is correspondingly impoverished with respect thereto.

Successful operation of a calutron depends upon the fulfillment of many unique conditions. For example, the ion source, the region surrounding the beam, and the isotope collectors must be enclosed within a reduced pressure vessel evacuated to the order of 10^{-5} to 10^{-4} mm. Hg. Such matters are hereinafter referred to but briefly, as it is with the ion beam producing mechanism, or "source" unit of the calutron with which the present invention is concerned.

A "source" unit for a calutron generally includes a chamber for holding a quantity of material, such as uranium tetrachloride, capable of being vaporized, a heater for the chamber, a cathode and an anode for establishing an arc discharge, and accelerating electrodes; the arrangement of these components being such that when heat is applied to the chamber by suitable means, the material vaporizes and is thence drawn through the electron stream of the arc discharge where dissociation takes place. The ions are thence drawn through a slit by the accelerating electrodes to form a beam which in turn is projected into the magnetic field as heretofore described.

Therefore it is emphasized, that in the operation of a calutron, it is necessary to vaporize the material desired to be ionized. Consequently there is created a problem related to the condensation of such vapor on the various operative parts of the device and the subsequent encrusting of the various operative parts with condensed vapor.

More particularly there is created the specific problem

2

of condensation of vapor on the sides of the arc slits whereby the formation of an excessive amount of the condensed vapor, or "crud," will seriously interfere with the calutron operation. "Crud" is described as a hard deposit of decomposed charge material, usually collecting on the arc slits or adjacent thereto, and is largely metallic.

In order to continue operation of the calutron it is necessary to remove this "crud" at regular periods during such operation and to this end the present invention comprises a calutron source embodying an improved device for removing encrusted materials adhering to the arc slits of a calutron ion source.

Heretofore, contributions to the art of slit cleaning as applied to calutron ion source units have comprised various means and have been used with varying success, none of them, however, being capable of decrudging the arc slits without subsequent damage to the slits or to the adjacent parts or otherwise failing because of their own mechanical structure and composition to perform the function for which they were designed. More specifically, considerable failure and consequent discontinuance of operation of the calutron has been associated with slit cleaner operation due to the binding of the cleaner blocks along the length of the arc slits and also failure and termination of operation due to binding of the mechanical linkage systems employed to project the slit cleaner blocks along the length of the arc slits.

It is therefore an object of this invention to produce an ion beam more efficiently, to decrease operational shutdown of the calutron and to prevent damage to arc chamber slits by providing an improved slit cleaning device to remove encrusted materials from the beam defining elements of a calutron ion source.

It is another object of this invention to provide a calutron ion source slit cleaner comprising a means for projecting the cleaning blocks in a straight line along the arc slits of a calutron ion source without binding within the arc slits and without damage to the said slits.

Another object is to provide a linkage and operating mechanism for projecting the slit cleaner blocks in a straight line along the length of the slits without binding of the component parts of the said linkage and operating mechanism.

Still another object is to provide a slit cleaner comprising a means for operating the said slit cleaner from outside the evacuated vessel without letting the said vessel down to atmosphere.

Further objects, advantages and features of the invention will be apparent from the annexed specification and claims considered together with the accompanying drawings, in which:

Figure 1 is a utility view of a calutron;

Fig. 2 is an enlarged sectional detail of a source unit as shown in Fig. 1, embodying the present invention and being taken on line 2—2 of Fig. 5;

Fig. 3 is a sectional view on a plane indicated by the line 3—3 of Fig. 2;

Fig. 4 is an enlarged view on a plane indicated by the line 4—4 of Fig. 2;

Fig. 5 is an enlarged view taken on line 5—5 of Fig. 1 showing the faces of the ion source chambers; and

Fig. 6 is an isometric view of one of the graphite scraper slides shown in detached position.

Referring to the drawings and more particularly to Fig. 1, there is illustrated a calutron including an electromagnet 13 having a pair of opposing pole pieces, only one of which, number 14, is shown, between which is positioned a vessel 16 adapted to be evacuated by suitable pumps (not shown). The vessel 16 includes a top wall 17, a bottom wall 18, a rear wall 19, side walls 20—21 and a removable front wall or door 22. Mount-

ed on the removable door 22 and projecting into the evacuated vessel 16 is an ion generating and transmitting mechanism indicated generally by 10, a beam liner 11, and isotope collectors generally indicated by 12.

Referring to Figs. 2, 3, 4 and 5, the ion generating and transmitting mechanism 10 comprises suitable charge reservoirs 23-24 within which are positioned removable charge bottles 26-27 adapted to be filled with a charge material such as uranium tetrachloride. This uranium tetrachloride charge material will vaporize when heated, such heat usually being supplied by electrical heaters as indicated by the numeral 25 on the drawing. The charge reservoirs 23-24 are provided with vapor manifolds 28-29 communicating with ionizing chambers 31-32 in which are disposed suitable baffles 33-34 adapted to break up the vapor flow and thus provide a uniform distribution of the vapor within the ionizing chambers 31-32. It is well understood in calutron operation that the vapor of the charge material will flow under pressure from the charge bottles into the vapor manifolds and thence through the baffles into the ionizing chambers.

The ionizing chambers 31-32 have the form of elongated slots and each chamber is provided with a cover plate 36-37 incorporating a V-shaped beam defining slit 38-39 generally of the length of the ionizing chambers 31-32, and disposed centrally thereof.

The source 10 also includes a pair of cathode stems 1 and 2 shown in Fig. 1 and Fig. 5 having their end portions overlying one of the extremities of the chambers 31-32, and in which are positioned suitable electron emissive cathodes 3 and 4, best shown in Fig. 5 electrically connected to leads entering through the cathode stems so that when a circuit is closed an electron stream is caused to flow the length of the ionizing chambers 31-32 to movable anodes 84-86 positioned at the other extremity of the chambers 31-32 and connected by any suitable leads, in the manner known in the art, to an electrical circuit (not shown). This electron stream ionizes the charge vapor, the vapor being thence projected into the magnetic field by means of accelerating electrodes 5 and 6 shown in Fig. 1, which accelerating electrodes are likewise connected to any suitable circuit, not shown.

Forming a part of the major supporting structure of the source 10 there is a rectangular frame casting 41 having a plurality of perpendicular legs attached thereto. Two of these perpendicular legs, 42, 43 are spaced apart on opposite ends of the casting 41 and together they support the brass frame casting 44 extending from one leg 42 to a point overlying the other leg 43. The guide frame casting 44 incorporates a machined guide slot 46 generally of its entire length, and into which is inserted the hatchet 47 which is securely attached by welds to the projecting lever arm 48.

The guide frame casting 44 also supports the triangular bell crank plate 49, one fulcrum point 49a of which is rotatably attached thereto by means of the pivot pin 51 threaded into the guide frame casting 44 and secured in place by the castellated nut 52. Another fulcrum point 49b of the bell crank 49 is rotatably attached to the link arm 48 by means of the pin 53 and is secured in position by the castellated nut 54, and still another fulcrum point 49c of the bell crank 49 is rotatably affixed to the offset link 56 by means of the pin 57 which is secured in place by a cotter pin.

The end of the lever arm 48 opposed to the hatchet 47 is rotatably attached to the linkage arm 58, the linkage arm 58 being slotted to receive the lever arm 48 and both arms 48 and 58 are joined by means of the pin 59 loosely fitted within an aligned machined hole in the arms 48 and 58 and is retained in place by means of a cotter pin. The other end of the linkage arm 58 is rotatably positioned on the frame 41 and is secured thereto by the threaded shoulder pin 61 which is loosely fitted

in the linkage arm 58 but securely clamped to the frame 41 by means of the castellated nut 62.

The other end of the offset link 56 opposed to the fulcrum point 49c is rotatably attached to the push-pull rod 63, the push-pull rod 63 being provided with a slot 5 to receive the offset link 56 and both of these members are joined by the pin 64 which is retained in place by means of a cotter pin.

The fulcrum pins 51, 53, 57, 59, 61, and 64 are preferably fabricated of a durable metal such as "Ampco," a copper base alloy that combines great strength and wear resisting qualities and are therefore utilized as an effective means to prevent binding of the pins employed in the linkage system.

15 The lever arm 48 projects beyond the hatchet 47 and is there provided with a cylindrical boss 66 rigidly fixed at right angles thereto and extending for equal lengths on each side thereof. The boss 66 is accurately drilled and reamed of its entire length to tightly receive 20 the rod 67 and the rod 67 is further secured to the boss 66 by a cotter pin to prevent rotation of the rod 67 within the boss 66. The ends of the rod 67 project beyond the ends of the boss 66 and are freely engaged within the slotted holes 68-69 of the cross piece lugs 25 71-72; the slotted holes 68-69 being of such length as to provide a free longitudinal motion of the rod 67 therein. The lugs 71-72 are firmly attached by welding to the slide cross piece 73; the cross piece 73 being of a length corresponding to the spaced-apart distance 30 of the ionizing chambers 31-32. Each end of the slide cross-piece 73 is bent 90° to provide entrance into the arc slit openings 38-39 where they engage the scraper slides 74-76 and are secured thereto by tightly fitted pins 77-78.

35 The scraper slides 74-76 support thin scraper blades 79-81 positioned at an angle on the scraper slides 74-76 and within the arc slits 38-39. The blades 79-81 are V shaped and correspond closely to the cross-sectional area of the arc slits 38-39 and have 30° 40 bevelled edges on the three sides thereof to provide a cutting edge that engages the parallel sides of the arc slits 38-39. The blades 79-81 being preferably formed of a hard and tough material, such as stainless steel, are suitable for use in scraping and removing the decomposed charge material or crud adhering to the arc slits 38-39.

Attached to the scraper slide pieces 74-76 by means of the shoulder screws 82-83, but situated interiorly of the arc members 31-32, are graphite scraper slides 84-86 that are generally of the width of the arc chambers 50 31-32. The scraper slides 84-86 are utilized to scrape condensed materials from the sides and front walls of the arc chambers 31-32 and, during operation of the calutron, are also used as anodes for the electron stream emitted from the cathodes. During operation of 55 the calutron, the scraper slides 84-86 functioning as anodes are positioned at the end of the arc chambers 31-32 opposing the cathodes.

Thus it is shown that the linkage system of the slit cleaner is loosely coupled to the slit cleaning system of 60 the device so that when the push-pull rod 63 is projected in the direction indicated by the arrow 87, motion in the direction indicated by the arrow 88 is transmitted to the hatchet 47 by means of the bell crank 49 and attached links 48-56, causing the hatchet 47 to slide along 65 the slotted guide 46 and also at the same time projecting the scraper slides 74-76-79-81-84-86 by means of the cross piece 73, along the length of the arc slits 38-39.

The hatchet 47 and accompanying scraper slides 74-70 76-79-81-84-86 are also returned to the operating position by means of applying a motion to the push-pull rod 63 in the direction indicated by the arrow 89. The length of the sliding motion of the hatchet 47 within the groove 46 is limited by the threaded regulating stop-screws 91-93 which are positioned on the end 75

of the guide casting 44 and are locked by means of the hexagonal nuts 92—94.

The threaded stop-screws 91—93 have slots 95 milled in one end thereof by means of which they are rotated to provide adjustment of the length of travel, of the hatchet 47; adjustment being necessary to limit travel of the slit cleaning scraper slides 74—76 along the length of the arc slits 38—39.

Although it is not shown on the drawings, it is generally understood that the push-pull rod 63 is operable from outside the evacuated vessel 16 and enters it by means of a vacuum seal housing mounted on the external side of the door 22 and having means such as a conventional seal on the interior thereof permitting of the longitudinal movement of the rod 63 without breaking the vacuum seal.

While there is herein disclosed what is at present considered a preferred embodiment of the invention, it will be understood that various changes and modifications may be made therein, and it is intended to cover all such changes and modifications as come within the true spirit and scope of the appended claims.

What is claimed is:

1. Apparatus for projecting an ion beam comprising walls defining an evacuated vessel, ion generating chambers having beam defining slits therein, scrapers mounted in the slits for longitudinal movement therein, means comprising a bell crank, scraper-actuating linkage mem-

bers associated with said bell crank, a hatchet associated with said linkage members, a guide casting having an elongated slot adapted to receive the said hatchet therein, stops positioned at opposite ends of the said guide casting for limiting longitudinal movement of the said hatchet along the said slot and means connecting said linkage and said scrapers for compelling longitudinal movement of the said scrapers along the said beam defining slits.

2. In combination with an ion generating chamber having an elongated exit slit therein, means for removing deposits from said slit and including, a scraper mounted in said slit for longitudinal reciprocating movement therewith, an actuating rod attached to said scraper, a bell crank pivoted upon a stationary support, means for rotating said bell crank, and a rotary to translatory movement converting linkage joining the bell crank and actuating rod, thereby to reciprocate said rod in a fixed plane upon rotation of the bell crank and to move the scraper along the slit without binding.

3. Apparatus as defined in claim 2 wherein said scraper comprises a first portion adapted to scrape the edge of the slit nearer the generating chamber and a second portion adapted to scrape the edge of the slit farther from the generating chamber.

4. Apparatus as defined in claim 2 wherein said chamber and said scraper actuating assembly are mounted upon a framework disposed interiorly of an evacuated vessel.
